UNITED STATES PATENT OFFICE.

HENRI VICTOR JULES JOUFFRET, OF PARIS, FRANCE.

CONTROLLING MEANS.

1,264,083.

Specification of Letters Patent. Patented Apr. 23, 1918.

Application filed August 25, 1917. Serial No. 188,205.

To all whom it may concern:

Be it known that I, HENRI VICTOR JULES JOUFFRET, engineer, citizen of the French Republic, residing at Paris, France, have invented certain new and useful Improvements in Controlling Means, of which the following is a specification.

This invention relates to controlling means and refers more particularly, although not exclusively, to apparatus of the kind in question intended for controlling the valves of motors.

The principal object of the invention is to construct apparatus of the class under consideration so that they can be more easily regulated and so that they are more simple than has hitherto been the case.

The controlling means is of the type in which there is provided between the operating part and the part to be operated, an intermediate part which part carries a roller or drum, by means of which the motion is transmitted either from the operating part to the intermediate part or from the intermediate part to the part to be operated, and the invention consists essentially in mounting the roller eccentrically with respect to an axle on the intermediate part and the furnishing means for turning the roller into and holding it in various positions for the purposes of taking up play or wear.

The invention comprises, in addition to the principal feature just mentioned, certain other features which will be explained more fully hereafter. It includes particular methods or constructions for carrying the said invention into effect and, as new industrial products, devices of the class in question embodying the said improvements, as well as special parts suitable for their construction and motors provided with the devices.

In order that the invention may be more clearly understood it will now be described with reference to the accompanying drawings, of which, as will be clearly understood is given merely by way of example.

Figure 1 of the said drawing is a side elevation of controlling means for controlling the valve of a motor by means of a cam, the device being constructed according to the invention.

Fig. 2 is a section on the line 2—2 Fig. 1.

The same letters of reference are employed to denote the same parts in both the views.

In the method of carrying out the invention more particularly illustrated in the

drawing and showing, as before stated its application to the control of valve mechanism from a cam, *a* is the cam and *b* is the valve rod which is to be operated through 60 an intermediate lever *c*.

According to the present invention two axles *c*¹ and *c*² are provided mounted on the lever *c*, and on each of these axles is mounted a roller, *d*¹ or *d*² in such a way that one 65 of the rollers is in contact with the cam *a* and the other with the extremity of the valve rod *b*.

One of the axles for instance the axle *c*² is so formed as to comprise an eccentric portion *c*²⁰ upon which is mounted the roller *d*², if desired with the use of an intermediate sleeve or casing *e*.

In this way, by turning the axle *c*² through a greater or less angle, the operation is regulated in an extremely simple manner, and means of compensation are provided for taking up any play which may exist.

In some instances, in addition to the arrangement or construction just described it 80 is desirable to provide the axle with means for locking it in any position into which it has been set when the regulation has been effected.

With this object in view it is preferable to 85 form the lever *c*, from two plates, between which are located the rollers *d*² and *d*¹. There is provided on one of the plates, around the hole provided for the passage of the axle, on the outer face of the plate an enlarged 90 portion *c*²⁰⁰ having teeth adapted to engage the teeth *c*⁰, and at the other extremity of the axle is a screw thread adapted to enable the said axle to be fixed with respect to the lever *c* by means of a nut.

In this way, in order to effect the regulation, it is sufficient to unscrew lightly the nut, in order to be able to disengage the teeth *c*²⁰⁰ from the teeth *c* to turn the axle *c*² through the desired distance and then to 100 screw up the nut again.

As will be readily understood, the invention is not limited to the particular construction herein described and shown in the accompanying drawings, as the construction 105 may be modified. For instance in some cases a simple plunger may take the place of the lever.

In general any modifications may be introduced within the scope of the appended 110 claims.

What I claim and desire to secure by Let-

ters Patent of the United States of America is:

1. Controlling means more particularly applicable for controlling valves of motors comprising an operating part, an operated part and an intermediate part, the latter adapted to receive motion from the operating part and to transmit it to the operated part, a roller on the intermediate part 10 through which the movement is transmitted from the operating part to the operated part, a pivot rotatably mounted on said intermediate part, said roller being mounted eccentrically with respect to said pivot and 15 means for holding said pivot in different positions of rotation with respect to said intermediate part to vary the angle of eccentricity of said roller.
2. Controlling means more particularly 20 applicable for controlling valves of motors comprising an operative part, an operated part and an intermediate part adapted to receive motion from the operating part and to transmit it to the operated part, a roller on 25 the intermediate part through which roller the movement is transmitted from the operating part to the operated part, a carrier upon which said roller is loosely and rotatably mounted, an axle upon the intermediate part with respect to which said carrier 30 is mounted eccentrically, and means for locking the axle in various angular positions.

3. Controlling means more particularly applicable for controlling the valves of motors comprising an operating part, an operated part and an intermediate part adapted to receive motion from the operating part and to transmit it to the operated part, the said intermediate part comprising two plates between which are located two rollers 40 through which the motion is transmitted, from the operating part to the operated part, one of the said rollers being mounted so as to rotate eccentrically upon an axle passing through the said plates, a projecting portion 45 around the aperture through which the axle passes on the outside of one of the plates, the said projecting portion being provided with teeth, an enlarged extension of the axle provided with teeth and adapted to engage with 50 the previously mentioned teeth, a screw threaded portion, at the other end of the axle coming beyond the other plate and a nut adapted to screw on to the said screw threaded portion of the axle all substantially 55 as and for the purposes set forth.

In testimony whereof I have hereunto set my hand in presence of two subscribing witnesses.

HENRI VICTOR JULES JOUFFRET.
